(Cl. D61—1)

To all whom it may concern:

Be it known that we, René Gardner and Hugo Bernzott, citizens of the United States, residing at Elmhurst in the county of Du Page, and Niles in the county of Cook, State of Illinois, respectively, have invented a new, original, and ornamental Design for Combined End Cap and Sleeve for Slat for Screens, of which the following is a specification, reference being had to the accompanying drawing, forming part thereof:

Figure 1 is a side elevational view of a combined end cap and sleeve for slat for screens, showing our new design.

Fig. 2 is a side elevational view of the disclosure in Fig. 1 with the cap and sleeve separated.

Fig. 3 is a top plan view.

Fig. 4 is a bottom plan view.

Fig. 5 is a top plan of the sleeve.

Fig. 6 is a bottom view of the sleeve.

We claim:

The ornamental design for a combined end cap and sleeve for slat for screens, as shown.

RENÉ GARDNER.
HUGO BERNZOTT.
